US0D1084368S

(12) **United States Design Patent** (10) **Patent No.:** **US D1,084,368 S**
(45) **Date of Patent:** **** Jul. 15, 2025**

(54) **LEAD PLACEMENT TOOL**

(71) Applicant: **SPR Therapeutics, Inc.**, Cleveland, OH (US)

(72) Inventors: **Matthew G. deBock**, Morrisville, NC (US); **Joseph W. Boggs, II**, Chapel Hill, NC (US); **Devin Sell**, Brecksville, OH (US); **Bradley A. Lewis**, Lyndhurst, OH (US)

(73) Assignee: **SPR Therapeutics, Inc.**, Cleveland, OH (US)

(**) Term: **15 Years**

(21) Appl. No.: **29/928,500**

(22) Filed: **Feb. 13, 2024**

Related U.S. Application Data

(62) Division of application No. 29/809,637, filed on Sep. 29, 2021, now Pat. No. Des. 1,021,113, which is a division of application No. 29/655,077, filed on Jun. 29, 2018, now Pat. No. Des. 934,438.

CLAIM

The ornamental design for a lead placement tool as shown and described.

DESCRIPTION

FIG. 1 is a perspective view of a lead placement tool showing our new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the figures are included for the purpose of illustrating portions of a lead placement tool and form no part of the claimed design.

1 Claim, 3 Drawing Sheets
